DESIGN FOR A SMOKING PIPE

Dexter Goulston and Oscar T. Edlund,
Detroit, Mich.

Application October 19, 1945, Serial No. 123,004

Term of patent 7 years

(Cl. D85—8)

To all whom it may concern:

Be it known that we, Dexter Goulston and Oscar T. Edlund, citizens of the United States, residing at Detroit, in the county of Wayne and State of Michigan, have invented a new, original, and ornamental Design for a Smoking Pipe, of which the following is a specification, reference being had to the accompanying drawing, forming part thereof.

We claim:

The ornamental design for a smoking pipe, as shown.

DEXTER GOULSTON.
OSCAR T. EDLUND.
